UNITED STATES PATENT OFFICE.

HAROLD PLUMMER, OF OAKLAND, CALIFORNIA.

AUTOMATIC TIME AND COIN-CONTROLLED SWITCH.

Application filed October 11, 1922. Serial No. 593,859.

To all whom it may concern:

Be it known that I, HAROLD PLUMMER, a British subject, residing at Oakland, county of Alameda, and State of California, have invented new and useful Improvements in Automatic Time and Coin-Controlled Switches, of which the following is a specification.

This invention relates to an automatic time and coin controlled electric switch, in which the closing of the motor circuit is controlled by a coin or like token inserted by the person desiring to operate the motor, and it also relates to means for automatically breaking the circuit through the motor and switch at the end of a predetermined time period.

The invention embodies an electric motor which may be employed for any purpose desired, a coin controlled switch whereby a circuit is closed through the motor, and an intermediate switch actuating mechanism driven by the motor and adapted to automatically break the circuit through the motor and switch at the end of a predetermined time period.

One form which my invention may assume is exemplified in the following description and illustrated in the accompanying drawings, in which—

Fig. 1 is a side elevation of an electric motor and the coin controlled switch with connected actuating mechanism.

Fig. 2 is a plan view of Fig. 1.

Fig. 3 is a central, vertical section of the coin controlled switch taken on line 3—3, Fig. 2.

Fig. 4 is a vertical cross section of the switch taken on line 4—4, Fig. 2.

Fig. 5 is a vertical section of the switch actuating mechanism.

Fig. 6 is a similar view taken on line 6—6, Fig. 2.

Referring to the drawings in detail, and particularly to Figs. 1 and 2, A indicates an electric motor of suitable construction, B a coin controlled electric switch, and C an intermediate switch actuating mechanism whereby the circuit through the switch and motor is automatically broken at the end of a predetermined time period. The switch proper is best illustrated in Figs. 3 and 4. It consists of a box like casing provided with front and end walls 2 and 3, respectively, side sections 4, top and bottom sections 5 and 6. Extending through the side

sections 4 of the switch box and suitably journaled therein is a cross shaft 7. Secured on the shaft interior of the box is a cam 8, and secured on the exterior end of the shaft, as indicated at 9, is a double ended lever 10, in the lower end of which is secured a crank pin 11. This pin is grooved, as at 12, to receive and form a guide for an actuating arm 13, hereinafter to be described.

The upper end of the lever 10 is provided with an inwardly extending pin 14, and a similar lever 15 secured on the opposite end of the shaft 7 is also provided with an inwardly extending pin 16. These pins engage a hooked end 17 of a slide plate 18 supported on the upper end of the box and this plate is guided by a pair of side lugs 19 as clearly shown in Figs. 1 and 2. Formed in the top section of the box indicated at 5 is a coin receiving slot 20. This slot communicates with a compartment 21 formed in an inner box 22, which is constructed of fibre or like insulating material. Projecting through the front plate or section of the box B, and also through the fibre or inner box 22, is a bolt 23, which forms one terminal of the electric circuit. Also extending through the front plate of the box B is a second terminal bolt 24, which forms a second terminal of the electric circuit. This terminal is connected through a wire 25 with the electric motor A and a circuit will only be formed through the motor and the switch when a coin is inserted and when the coin makes engagement with the terminals 23 and 24. This is accomplished in the following manner:

Mounted in the rear portion of the inner switch box 22 is a plunger 26. This plunger is normally held in an extended position by means of a spring 27, and when so extended leaves the slot 21 open. The outer end of the bolt is provided with a head 28 and this is engaged by the cam 8 and actuated thereby as will hereinafter be described. The bolt when acted upon by the cam 8 is moved inwardly and across the coin slot 21 and a recess is formed in the inner end of the terminal bolt 24 as shown at 24a to receive the bolt 26. When it is desired to form a circuit through the motor A, the hooked end of the cover plate 18 is grasped and pulled rearwardly in the direction of arrow α . (see Fig. 3.) Such movement uncovers the coin slot and per-

mits insertion of a coin and it at the same time imparts a turning movement to the shaft 7 and the cam 8 secured thereto. This turning movement swings the cam in the direction of arrow *b* and the cam will thus engage the head of the bolt 26 and will force it inwardly and across the coin slot 21. Therefore if a coin is inserted through the upper end of the slot, it will drop downwardly into the inner switch box 22 and it will here be temporarily supported as further progress of it is interrupted by the terminal bolt 23 and the bolt 26; this being plainly shown in Fig. 4, as the coin is there indicated by the numeral 30. The coin, in other words, forms a connection between terminal members 23 and 24 and in this manner closes a circuit through the motor. This circuit would be permanently closed and maintained unless means are provided for retracting the bolt 26 so that the coin may be released and the circuit broken, and a mechanism is therefore provided whereby such release is accomplished. This mechanism will hereinafter be referred to as the intermediate switch actuating mechanism; the mechanism employed being best illustrated in Figs. 5 and 6.

The mechanism consists of a casing constructed of two sections, as indicated at 31 and 32. These sections are bolted together at 33 and as such form a housing or casing in which is journaled a series of shafts, as indicated at 34, 35 and 36. These shafts 35 form a support for a worm gear reduction train, which consists of a pinion 38, a worm gear 39, a pinion 40, and a worm gear 41; the pinion 38 being secured on shaft 34, the pinion 40 and the gear 39 being secured on the shaft 35, and the final reduction gear 41 on the shaft 36. The actual reduction employed or obtained in this instance is one thousand to one, that is shaft 35 is driven by the motor A through the pulleys 42 and 43, and the belt 44 and the reduction is such that one thousand revolutions of shaft 34 will be required to rotate shaft 36 one revolution. Secured on one end of shaft 36, which extends through the casing, 50 is a crank arm 45, and pivotally attached thereto, as at 46, is the switch actuating arm 13 heretofore referred to. This arm is supported by the crank pin 11 and is guided by the groove 12 formed therein. Formed on the arm 13, adjacent its outer end, is a shoulder 13^a, and attached to the extreme outer end of the arm is a spring 50, which holds arm 13 in engagement with the crank pin 11. Arm 15, which is secured on shaft 60 7, is connected to a coil spring 52 and the opposite end of this spring is attached to the lower end of the switch box B, as shown at 53. This spring is so positioned that its upper end will swing beyond a vertical line drawn through the center of the shaft 7.

Therefore when cover plate 18 is moved to open position, spring 52 will assume the position shown in Fig. 1, thereby retaining the cover plate in open position and also the shaft 7 in its turned position, where cam 8 engages bolt 26. It may here be stated that the tension of the spring 52 is greater than the tension of the spring 27, which surrounds the bolt 26, and it will for this reason retain the bolt in its forward or depressed position until it is automatically released by the intermediate switch actuating mechanism C. This is accomplished as follows:

Formed on one side of the crank pin 11 is a flattened face 11^a. This face is adapted to be engaged by the shoulder 13^a and when such engagement is made, movement will be imparted to swing the arm 10 back to normal position. This movement is imparted during the last portion of the single revolution of shaft 36 and the only movement required is just sufficient to swing the lever 10 slightly beyond a vertical position as the spring 52 will complete the movement the moment it passes beyond a central, vertical line drawn through shaft 7.

An electric motor connected and controlled as here shown may be used for a number of different purposes. For instance to drive a shoe polishing machine which is intermittent in operation; a fan or in fact any mechanism desired which is not continuously used, for instance if the motor A was connected to a shoe polishing machine and practice determines that it only takes three minutes to polish a pair of shoes, then it is obvious that the circuit should be broken through the switch and motor at the end of three minutes. The gear reduction employed and the speed of the motor would then be regulated so that it would take three minutes to impart one revolution to the shaft 36. This one revolution would cause the shoulder 13^a of arm 13 to engage the flattened face of the crank pin 11, and lever 10 would therefore swing back to normal position when so engaged, the first movement of arm 10 being imparted through arm 13 and the shoulder 13^a and the last movement by the pull of the spring 52 when the spring passes over the center. Bolt 26 will be automatically retracted by the action of the spring 27 when cam 8 moves away from the bolt, and the coin 30 will then be released and the circuit through the switch and the motor broken. The time period required to break the circuit may be entirely regulated by reducing gears, and it is therefore possible to break the circuit after the motor has been operated for one minute, three minutes, five minutes, or in fact any time period desired. The cover plate 18 is also returned when the circuit is broken and the coin slot is therefore covered. This is

of importance as the next person desiring to operate the motor, or in other words the mechanism driven thereby, will first have to push the cover plate back to uncover the 5 coin slot and when so doing resets the switch terminals to receive the coin, which will then close the circuit and again set the motor in operation.

While certain features of the present invention are more or less specifically illustrated, I wish it understood that various changes in form and proportion may be resorted to within the scope of the appended 10 claims, similarly that the materials and finish of the several parts employed may be such as the experience and judgment of the manufacturer may dictate or various uses 15 may demand.

Having thus described my invention, what 20 I claim and desire to secure by Letters Patent is—

1. The combination with an electric motor and a coin controlled switch therefor of means requiring manual setting of the 25 switch before a coin can be inserted and the circuit closed, and means driven by the motor for resetting the switch and releasing the coin to break the circuit.

2. In a device of the character described 30 an electric switch, comprising a casing, a shaft extending therethrough, a cam on the shaft, a plunger actuated by the shaft and

adapted to prepare a circuit which is closed by the insertion of a coin, a motor in the circuit, and means driven by the motor for 35 releasing the plunger and the coin for breaking the circuit through the motor.

3. In a device of the character described, an electric switch comprising a casing, a switch lever on one side of the casing, a 40 shaft adapted to be turned thereby, a cam on the shaft, a plunger actuated by the cam and adapted to prepare an electric circuit, which is closed upon insertion of a coin, an electric motor in the circuit, a reduction 45 gear driven thereby, and means actuated by said reduction gear and engageable with the switch arm to swing the same to open position.

4. In a device of the character described, 50 an electric switch, a switch arm thereon, a shaft connected to the arm and adapted to be turned thereby, a cam on the shaft, a plunger actuated by the cam and adapted to prepare a circuit which is closed by the 55 insertion of a coin, a motor in said circuit, a reducing gear driven by the motor, a crank arm driven by the reducing gear, and an arm connected to the crank arm and engageable with the switch arm to swing the 60 switch to open position and thereby return the cam and the plunger and release the coin whereby the circuit was closed.

HAROLD PLUMMER.
